18 Claims. (Cl. 51—95)

1

My invention relates to a method for producing, starting from a steel spindle or needle and in a single operation, boring drills; said method consists chiefly in cutting or recessing by means of a grindstone rotating at a high speed at least one flute of the drill in a steel needle advancing in the direction of its longitudinal axis while rotating about said axis, the longitudinal displacement of the needles to be machined on one hand and the rotation of the grindstone on the other hand being executed with a sufficiently high speed for the steel shavings removed from a needle by the grindstone not to have time to communicate their heat to the mass of metal forming the needles.

By way of example I may mention that in the case of drills the diameters of which are 3 mm. and which are to be provided with flutes 50 mm. long, the time of reciprocation of the drill should not be above $\frac{1}{4}$ of a second, the translation speed reaching up to one meter per second and the grindstone moving at a linear speed of at least 80 meters per second.

The automatic machine for producing the drills includes chiefly two grindstones one of which is intended for recessing the flutes and the other for the cutting or production of the fillets, said grindstone being associated with means for imparting to the steel needles a combined longitudinal and rotating movement with reference to each of the grindstones, the recessing grindstone having its axis oblique with reference to the direction of displacement of the needles while the cutting grindstone has its axis parallel with said displacement.

Means may be provided for transferring automatically the drill from the zone of operation of the recessing grindstone into the zone of operation of the cutting grindstone. Preferably these means may be operative at the end of the feed stroke of the needles during which the flutes have been recessed while the cutting is produced during the return stroke of the needles.

Further features of the machine according to my invention will appear in the following description of a form of execution of a machine selected by way of example and illustrated in accompanying drawings.

In said drawings:

Fig. 1 is a large scale view of a drill;

Fig. 2 is a cross-sectional view of said drill;

Figs. 3 and 4 are diagrammatical showings adapted to explain the general operation of the machine;

2

Fig. 5 is a plan view, partly cross-sectional, of the central portion of the machine;

Fig. 5a is a plan view, partly cross-sectional, of the right hand end of the machine;

Fig. 6 is a plan view of the left hand end of the machine together with the grindstones and their controlling means;

Fig. 7 is a plan view of the right hand end of the machine with the device for introducing the needles;

Fig. 8 is a detail, on a larger scale, of a part of the machine comprising a sun-and-planet system and a shaft controlled by said system;

Fig. 9 is an elevational view of the central part of the machine;

Fig. 10 is an elevational view of the left hand side of the machine with the grindstones;

Fig. 11 is an elevational view of the right hand side of the machine;

Figs. 12 and 12a form a rear view of the machine;

Fig. 13 is a detail view in longitudinal cross-section and at a larger scale of the clamping means and auxiliary members;

Fig. 14 is a transversal cross-section through line A—B of Fig. 13;

Fig. 15 is a detail view of a transmission gear;

Fig. 16 is a detail elevational view of the needle distributor of the machine.

20 Reverting to Figs. 1 and 2, they show a drill constituted by a cylindrical rod T wherein are cut the helical flutes G. There exists two such flutes at 180° from one another. At the end of each flute in the direction of engagement of the 25 drill there is provided a small rib or fillet L adapted to open the way for the drill in the material engaged thereby in order to avoid any friction between the wall of the bore being made and the surface of the drill.

20 According to my invention (Figs. 3 and 4), there are used two grindstones M, M' rotating both around stationary axes. The first grindstone M is the so-called flute recessing grindstone and lies at a certain angle with reference to the

axis of the cylindrical rod T. A needle adapted to be made into the form of a drill is introduced in front of said grindstone and rotates with reference thereto, while executing a longitudinal movement in the direction of the arrow f. Under these conditions and during the movement 45 the flute is recessed through the action of the grindstone M.

The drill is then submitted as a whole to a 50 bodily downward movement as illustrated by the arrow g and this displacement engages it with

the so-called relieving grindstone M' the axis of which is parallel to that of the drill. Now if the drill is caused to advance from right to left as shown by the arrow h, while rotating this combined movement is identical with and of opposite direction with reference to that executed by the drill for recessing the flutes and the grindstone M' provided with a suitable flat surface will wear off the parts located between the flutes so as to shape them into a cylindrical surface with the exception of the rib which remains then as a projecting rib on the drill.

Lastly the drill is returned into its upper position while it is caused to rotate through 180° round its axis so that the second flute may be recessed during the next feed.

The machine according to my invention includes a base plate 1 carrying a frame 2. The frame carries in its turn two uprights 4 and 5 (Figs. 5 and 12); these two uprights form the bearings of a rocking cradle including a central hollow member 6 pivotally carried in said uprights 4 and 5 together with two horizontal beams 7 and 8 connected at their front end by the stationary cross-beam or head 9. This cross beam is rigid with a guiding sleeve 11. The rear ends of the longitudinal beams 7 and 8 are connected through a further cross member 12 adapted to slide over them. This cross member 12 is provided with a bearing inside which may rotate without its being capable of moving longitudinally a hollow spindle 13 ending with a nose 14 screwed into same (Fig. 13). Inside said spindle may move a clamp 15 formed after the manner of all similar clamps by a plurality of segments adapted to cooperate with the nose 14 (Fig. 14). This clamp 15 is rigidly secured through screwing with a clamp drawing member 16 fitted at its rear end inside a nut shaped pinion 17 adapted to be screwed into or to be unscrewed from the cross member 12. Obviously the rotation of the nut shaped pinion 17 has for its action to provide for the forward or the rearward movement of the clamp drawing member inside the spindle 13.

The clamp drawing member 16 is provided with an axial bore inside which advance the succession of needles or spindles of tempered steel 18, the forward needle of which is being machined so as to form the drill.

The nut-shaped pinion 17 receives its rotational movements in either direction through a gear 19 keyed to a shaft 21 adapted to rotate without any longitudinal movement in the cross member 12. This gear 19 is rigid with a ribbed spindle 22 adapted to move freely in a longitudinal direction inside the fluted hub of a bevel pinion 23 and rotating in unison with said hub. The bevel pinion 23 meshes with another bevel pinion 24 housed inside a casing 25 secured to the longitudinal beam 8 (Fig. 5). The shaft 31 carrying the pinion 24 is rigid with a toothed plate 26 meshing with a toothed socket 27; said toothed socket is submitted to the action of a spring 28 bearing against a ring 29 secured to the shaft 31 of the pinion 24, which shaft is mounted in its turn inside the head of the connecting rod 32 adapted to rotate freely round the shaft of a motor 33 which is the motor controlling the opening and closing of the clamp. The shaft of said motor 33 carries on the other end a pinion 34 meshing with the gear wheel 35 rigid with the toothed socket 27. It is apparent that the cooperation between the toothed socket 27 and the toothed plate 26 forms a stress limiting device, i. e. when the resistance opposed by the plate 26

is too high, the socket 27 rotates round the shaft 31 without driving the plate or the shaft 31. The mounting of the shaft 31 inside the connecting rod 32 allows the rocking of the cradle 6 and of its longitudinal beams 7 and 8.

I will now describe the members providing for the helical displacements of the spindle 13 in order to allow the recessing of the gouges. A reproducing device 36 (Figs. 8 and 9) constituted by an externally threaded sleeve is rigid with the spindle 13. This threaded sleeve is slightly conical and ends at its front end into a cylindrical part 37. Its threaded portion cooperates with a cylindrical nut 38 rigidly secured through the agency of a sleeve 39 to a flange 41 on a further sleeve 42 adapted to rotate inside the hollow central portion 6 of the cradle. The flange 41 carries moreover a projection 43 adapted to cooperate with two stops 44 and 45 secured respectively to the longitudinal beams 7 and 8 of the cradle. The cooperation between said projection 43 and the stops 44 and 45 limits to 180° the rotation of the flange 41 and consequently of the nut 38.

The sleeve 42 carrying at the end opposed to the flange 41 a bevel wheel 46 is fitted over another sleeve 47 capable of sliding without any rotation over the spindle 13 by reason of the presence of a key 48. Said sleeve 47 ends with a bevel wheel 49 coaxial with the bevel wheel 46.

The bevel wheel 49 meshes with the bevel wheel 51 secured to the end of a shaft 52 the other end of which is keyed to one of the sunwheels 53 of a sun-and-planet system the planet pinions 54 of which are carried inside a cage 55 rigid with a gear 56.

The bevel wheel 46 meshes with a bevel wheel 57 secured to its hollow shaft 58 adapted to rotate inside the central member 6 of the cradle. To said hollow shaft 58 is keyed a gear 59.

Furthermore the second sunwheel 61 of the sun-and-planet system is keyed to a shaft 62 rigid with a pinion 63. This shaft 62 is carried inside bearings forming part of an extension of the frame 2, as shown in Fig. 12. The pinion 63 engages a gear wheel 64 engaging in its turn a pinion 65 keyed to a shaft 66 adapted to rotate inside the bearing 67 secured to the frame. The axis 68 of the gear wheel 64 is capable of moving as shown in Fig. 9 inside its slideway 69 formed in a member 71 of a so-called swing frame provided with a collar 72 surrounding the shaft 66 and adapted to rotate round same. The member 71 shown in Fig. 9 has been illustrated separately in Fig. 15. It is provided with a slot 73 concentric with the shaft 66 and adapted to receive a securing screw 74 engaging the frame and allowing consequently said member 71 to be set in different angular positions with reference to the shaft 66. This arrangement allows changing the pinion 65 by suitably modifying the position of the axis 68 in its slideway 69 and the position of the swing frame 71 through a rotation thereof with reference to the screw 74.

The shaft 66 carries moreover a pinion 75 (Fig. 12) projecting through an opening 76 of the frame. The pinion 75 is engaged by a toothed sector 77 (Fig. 9) keyed to a shaft 78 carried by the frame. A counterweight 79 balances the sector 77 as shown in Fig. 11. To the shaft 78 is also keyed an arm 81 pivotally secured to a connecting rod 82. The latter is pivotally secured to the end of a crank 83 keyed to a shaft 84 carried in the frame and the other end of which is provided with a toothed wheel 85 (Fig. 12a) meshing with a pinion 86 to the axis 87 of which

is keyed the wheel 88 meshing with the pinion 89 keyed to the axis of the motor 91 which is the drill controlling motor.

The gear 59 meshes with the gear wheel 92 (Figs. 8 and 12) and the gear 56 meshes with the gear 93, both gears 92 and 93 being rigid with a common shaft 94 mounted in and passing through the frame. At its other end, the shaft 94 carries a gear wheel 95 engaging a pinion 96 keyed to the shaft of the motor 97 which latter is carried by a bracket 98 of the frame. Said motor 97 is the motor controlling the reversing of the drill (Fig. 12a).

As already disclosed, the bevel reproducing sleeve 36 ends under the form of a cylindrical ring 37 (Fig. 9). The member 36 and its ring are adapted to cooperate with a roller 101 carried inside a strap 102 the threaded tail-piece of which may be adjusted through suitable nuts with reference to the transversal member 103. Said transversal member 103 is pivotally secured on one hand at 104 to an upright 105 of the frame and is secured on the other hand through a bolt to the opposite upright 106 of the frame (Figs. 12 and 12a). The uprights 105 and 106 are provided moreover with stops 100 against which may bear the longitudinal beams 7 and 8 which are urged against same through the springs 107 acting on said longitudinal beams 7 and 8 of the cradle and bearing on the other hand against nuts 108 engaging screws 109 fitted in the frame. These stops 100 prevent the reproducer 36 or its ring 37 from engaging roughly the roller 101 when the cradle is being raised. They are located in a manner such that there is no complete contact between the reproducer and the roller in the raised cradle. The lowering of the cradle is provided through a cam 111 as shown in particular in Fig. 9, said cam acting on a bar 112 rigid with the transverse or head beam 9. Said cam 111 is keyed to a shaft 113 rotating inside the bearing 114 secured to the frame as shown in Fig. 5. The shaft 113 is provided with a gear wheel 115 meshing with a pinion 116 keyed to the end of the shaft of the motor 117 which is the cradle lowering motor and is carried by a support 118 secured to the frame (Fig. 9).

The distribution of the drills forming steel needles or spindles 18 is provided through a gravity distributor (Figs. 5, 11 and 16) constituted by two plates 119 and 121 between which the spindles or needles 18 are adapted to progress. The lowermost needle registers with the opening of the clamp drawing member 16 and it is urged into the channel formed inside said member by a piston 122 secured to the end of a slider 123 (Fig. 11) adapted to move inside a frame 124 and operatively engaged at its other end by a connecting rod 125 pivotally secured to a crank 126 (Fig. 7) carried by a plate keyed to the end of the shaft of the needle introducing motor 121. Said shaft is provided at its other end (Fig. 11) with a projection 128 adapted to cooperate with either side of a stop 129 secured to the frame 124. This frame 124 is carried in its turn together with the motor 121 on a slider 131 which it is possible to displace with reference to the frame of the machine through a nut and screw system actuated by a hand wheel 132.

Once they have engaged the channel of the clamp drawing member 16, the needles 18 (Fig. 13) move forward and push one another forwardly inside said channel. A spring urged hook 133 secured to the clamp drawing member prevents the latter from moving out of the channel.

To the forward end of the clamp drawing member is threadedly connected as disclosed the clamp 15. Said clamp is constituted as known per se (Fig. 14) by a certain number of segments which have a tendency to moving apart and which are urged together so as to fasten the foremost needle between them through the agency of the conical nose 14 secured through screwing to the end of spindle 13 when the clamp drawing member advances with reference to said spindle. On the contrary when the clamp drawing member recedes the needle is released. Care should be taken to avoid this release from being too rough and leading to an ejection of the needle. To this purpose I resort to the arrangement illustrated in Figs. 13 and 14. The clamp 15 is provided in its rear part with a slope 134 adapted to cooperate with the yielding segments 135, the tail ends of which are rigid with the conical nose 14 and consequently with the spindle 13. It is apparent that when the clamp 15 recedes its rear slope cooperates with the ends of the segments 135, which ensures a certain fastening of the clamp and consequently a braking of the movement of the finished drill which is ejected only subsequently under the action of the progression of the next needle which enters its shaping position.

The grindstone M for recessing the flutes is keyed to a spindle 137 (Figs. 6 and 10) rotating inside a bearing 138 forming part of a slider 139 adapted to move vertically inside a frame 141 carried by a sector-shaped plate 142. Said plate 142 may rotate round an axis 143 passing through the point of engagement between the grindstone and the drill. Said plate is provided with screws 144 adapted to move inside a groove 145 the center of which is at 143 and which is formed on the base plate 1 of the machine. It is possible thereby to adjust the angular position of the grindstone M with reference to the axis of the drill. The grindstone M is started running through a pulley 146 keyed to the shaft 137 and connected through a belt 147 to a companion pulley 148, keyed to the shaft of the motor 149 pivotally secured to the frame 141. Tensioning means 151 allow moving the pulleys 146 and 148 together or apart. On the other hand the vertical movements of the slider 139 with reference to the frame 141 are obtained through a flywheel 152 (Fig. 10) carried by the frame 141 and the threaded axis 153 of which cooperates with a nut 154 rigid with the slider 139.

The relieving grindstone M' (Figs. 5 and 8) is carried at the end of an axis 155 adapted to rotate inside the bearing 156 under the action of a motor 158 as transmitted through a belt 151. The motor 158 and the bearing 156 are carried by a slider 159 which may be displaced through a slideway 161 through the usual means not illustrated controlled by a hand wheel 162. The slideway 161 is rigid with the plate 163 secured to the base plate 1 of the machine.

Lastly a control of any known type 164 which need not be described more fully allows sending current at the desired moments of the operating cycle of the machine to the motors 33, 127, 97 and 117. For the sake of simplicity I have merely shown on said controller and on the motors considered the starting points of the connections without illustrating the connections themselves.

The controller is started through a gear 165 engaging a pinion 136 (Fig. 9) to the axis of which is keyed a bevel wheel 167 meshing with the bevel

wheel 168 keyed to the shaft 84 driven by the motor 91.

As for the motors 149 and 158 controlling the grindstones M and M' there is provided for them no connection with the controller as they are adapted to rotate in a continuous manner.

The operation of the machine is as follows:

The operator begins filling the gravity distributor 119-121 with needles 18. Said needles sink inside the feed channel formed between the plates 119 and 121. The crank plate 126 is then operated by hand for introducing the needles into the channel of the clamp drawing member 16. As they pass, the needles raise the spring urged hook 133 which holds them when the channel is full and the first needle is in its operative position in the clamp 15.

The operator, after he has cut the grindstone M to the desired flute shape and after having ground in proper parallelism with its axis the grindstone M', adjusts these two grindstones by placing them in a manner such as they may remove the amount of metal required. This being done he provides for the slope to be given to the grindstone M in relationship with the thread pitch to be obtained on the drill, by displacing in a suitable manner the screws 14 inside the circular groove 145 of the base plate 1.

He sends then current into the grindstone controlling motors 149 and 158 and then into the motor 91. The latter through the agency of the shaft 84, of the rod 82, of the arm 81 and of the shaft 78 rocks the sector 77. The stroke of the connecting rod 82 and the gear ratio between the sector 77 and the wheel 75 meshing therewith are selected in a manner such that for each revolution of the crank, the wheel 75 may execute one revolution towards the right and one revolution towards the left. The wheel 75 through the shaft 66 and the gear wheels 65, 64 and 63 causes the shaft 62 to rotate. The reducing ratio is adjusted through the swing frame 71 for instance in a manner such that to each revolution of the wheel 75 may correspond two revolutions of the wheel 63. The shaft 62 executes therefore two revolutions towards the right and two towards the left. The sunwheel 61 of the sun-and-planet system which is keyed to the shaft 62 produces through the agency of the planet pinions 55 a rotation in opposite direction of the other sunwheel 63 which leads to a rotation of the shaft 52 and of the pinion 51. The latter acts in its turn through the agency of the bevel wheels 51 and 49 on the sleeve 47 the rotation of which drives the spindle 13 and consequently the reproducer 36 which is screwed inside the nut 38 acting as a stationary nut. Thereby the reproducer advances helically with reference to the grindstone M which recesses the needle driven by the spindle and forms a helical flute therein. The conicity of the reproducer 36 cooperating with the roller 101 has for its action to slightly depress the cradle 7, 8 and 9 as the needle progresses forwardly, which allows the obtention of a gradual reduction of the depth of the flute rearwardly.

When the drill is at the end of its stroke, as illustrated in Fig. 13, after recessing of the first gouge, the controller 164 sends current into the motor 117. The latter acts through the agency of the pinion 116, of the gear wheel 115, of the shaft 113 and of the cam 111 acting on the bar 112 so as to depress the head cross-members (Fig. 11) and consequently the cradle whereby the drill is brought into operative relationship

with the finishing grindstone M' adapted to remove the material at the periphery of the drill except for that forming the ribs or fillets while the reproducer is unscrewed with reference to its nut 38 and returns into its original position by reason of the reversal in the direction of rotation of the shaft 52 and of the bevel wheel 51.

At the end of this return movement, the controller 164 sends current of opposite direction into the motor 117. The latter rotates in the opposite direction and the cam 111 releases the bar 112 whereby the cradle returns into its upper position for which the ring 37 is again almost in contact with the roller 101.

On the other hand the controller has sent current into the motor 97 which, through the agency of the shaft 94 (Fig. 8) and of the gear wheel 93 causes a rotation of the wheel 56 with the cage 55 of the sun-and-planet system including the planet pinions 54 driving in their turn the sunwheel 53 of said system together with the shaft 52, the bevel wheels 51 and 49 and the spindle 13 which is screwed thus into the reproducer. If the gear ratios have been suitably chosen the spindle 13 executes thus a half revolution round its axis and the drill occupies the position required for recessing the second flute at 180° of the former flute.

But obviously by providing such a half revolution of the spindle 13 and consequently of the reproducing sleeve, said spindle progresses through the length of a half pitch and if this difference were not corrected at the end of a few cuts, the reproducer would finally be screwed home inside the nut 38 and the machine would be locked.

This is corrected through the arrangement constituted by the pinion 92 keyed to the shaft 84 carrying also the pinion 93. The pinion 92 acting on the wheel 59 causes a rotation of the wheel 57 and of the bevel wheel 46, which leads to the rotation of the sleeve 41, of the flange 42, of the socket 39 and of the nut 38. This constrains the spindle 13 to move backwards through a half pitch in compensation with the forward half pitch progress produced through the action of the sun-and-planet system. The relative axial position of the reproducer 36 and of the nut 38 remains thus unaltered.

When returned into its rear starting position, the drill is urged forwardly again for recessing the second flute and for the formation of the fillet, the operation being the same as disclosed preceedingly. Preferably the cycle begins over again twice more for the finishing of the two flutes, i. e., for the removing of the last unevenesses to be ground off the flutes and the surface of the drill.

Lastly, when the last cut is finished and the cradle has returned into its upper position, the controller 164 sends current into the motor 33 which through the agency of the pinion 34, of the gear 35 and of the stress-limiting device 26, 27 causes the bevel wheels 24, 23 to rotate, which drives the gear wheel 19 (Fig. 13) and the nut-shaped pinion 17. The latter as it is unscrewed with reference to the cross member 12 urges rearwardly the clamp drawing member 16 which makes the clamp 15 recede and release the finished drill, the latter is released and held then through the segments 135 so that it can no longer be ejected until it is urged forwardly by the following needle 18.

In the meantime, the controller 164 has sent current into the motor 127 which has begun ro-

tating and has urged forwardly through the agency of the crank plate 126, of the connecting rod 125 and of the slider 123, the needle introducing piston 122 which urges a further needle inside the channel of the clamp drawing member 16. The movement of the motor is stopped when the projection 126 meets the stop 129. The finished drill is ejected by the needle following it and which engages its operative position.

The controller 164 sends then current of opposite direction into the motor 33 which causes the clamp drawing member 16 and the clamp 15 to advance while locking the front needle in the position occupied by it.

The cycle of operation is then at an end and a further cycle may be begun.

My improved machine may produce drills of different sizes both as to diameter and to length. To this purpose it is possible to change the clamp 15 and the clamp drawing member 16 the cylindrical part of which latter may be more or less elongated so that its length may be a predetermined multiple of the length of the needle, while its channel may receive a more or less considerable diameter. It is also possible to change the reproducer 36 and its nut 38 together with the distributor which is adjustably secured to the base plate in a manner such that it is possible to modify its position in accordance with the length of the clamp drawing member. Lastly it is also possible to change the needle introducing piston 122.

What I claim is:

1. A machine for producing drills starting from elongated members comprising a first grindstone adapted to recess the flutes in the elongated members, means for rotating same at a very high speed, a second grindstone for relieving the periphery of the drills except in the vicinity of the flutes for forming ribs along same, means for imparting to an elongated member a combined movement longitudinally to and round its axis during operation with each grindstone in succession, along lines respectively oblique with reference to the axis of the grindstone and parallel with that of the relieving grindstone and means pivoted on a horizontal axis in the machine for transferring automatically the drills from the zone of operation in which they lie along the first of above mentioned lines into the zone of operation of the second grindstone along the second mentioned line.

2. A machine for producing drills starting from elongated members comprising a first grindstone adapted to recess the flutes in the elongated members, means for rotating same at a very high speed, a second grindstone for relieving the periphery of the drills except in the vicinity of the flutes for forming ribs along same, means for imparting to an elongated member a combined movement longitudinally to and round its axis during operation with each grindstone in succession, along lines respectively oblique with reference to the axis of the first grindstone and parallel with that of the relieving grindstone and means pivoted on a horizontal axis in the machine for transferring automatically the drills from the zone of operation in which they lie along the first of above mentioned lines into the zone of operation of the second grindstone along the second mentioned line, means for operating said transfer means at the end of the forward movement of the elongated members corresponding to the recessing of the flutes and means whereby the second grindstone is operative dur-

ing the return movement of the elongated members along the corresponding line.

3. A machine for producing drills starting from elongated members comprising a first grindstone adapted to recess the flutes in the elongated members, means for rotating same at a very high speed, a second grindstone for relieving the periphery of the drills except in the vicinity of the flutes for forming ribs along same, means for imparting to an elongated member a combined movement longitudinally to and round its axis during operation with each grindstone in succession, along lines respectively oblique with reference to the axis of the first grindstone and parallel with that of the relieving grindstone and means pivoted on a horizontal axis in the machine for transferring automatically the drills from the zone of operation in which they lie along the first of above mentioned lines into the zone of operation of the second grindstone along the second mentioned line and means for turning the elongated member after one reciprocation of the elongated member through 180° round its axis.

25 4. A machine for producing drills starting from elongated members comprising a first grindstone adapted to recess the flutes in the elongated members, means for rotating same at a very high speed, a second grindstone for relieving the periphery of the drills except in the vicinity of the flutes for forming ribs along same, means for imparting to an elongated member a combined movement longitudinally to and round its axis during operation with each grindstone in succession, along lines respectively oblique with reference to the axis of the first grindstone and parallel with that of the relieving grindstone and means pivoted on a horizontal axis in the machine for transferring automatically the drills from the zone of operation in which they lie along the first of above mentioned lines into the zone of operation of the second grindstone along the second mentioned line and means for gradually moving the elongated member away from the first grindstone during operation of the latter for reducing gradually the depth of the recessed flute.

35 5. A machine for producing drills starting from elongated members comprising a grindstone adapted to recess flutes in the elongated member, means for rotating same at a very high speed, a hollow spindle inside which the elongated members are adapted to move in succession, chuck members mounted at the end of said hollow shaft facing said grindstone for retaining and releasing the first one of said elongated members, a cradle carrying said hollow spindle, a horizontal pivot round which said cradle is adapted to rock, a second grindstone adapted to engage the elongated members the flutes of which have been recessed by said first grindstone for relieving its surface 40 the axis of said pivot being in the same plane as the cradle pivot and means for applying to the hollow spindle a rotary and translational movement with reference to the cradle.

45 6. A machine for producing drills starting from elongated members comprising a grindstone adapted to recess flutes in the elongated member, means for rotating same at a very high speed, a hollow spindle inside which the elongated members are adapted to move in succession, chuck members mounted at the end of said hollow shaft facing said grindstone for retaining 50 and releasing the first one of said elongated

75

members, a cradle carrying said hollow spindle, a horizontal pivot round which said cradle is adapted to rock, a second grindstone adapted to engage the elongated members the flutes of which have been recessed by said first grindstone for relieving its surface the axis of said pivot being in the same plane as the cradle pivot, a threaded reproducing member rigid with the hollow spindle and a nut cooperating therewith for imparting to the spindle and to at least the foremost elongated member in the spindle a rotary and translational movement for the recessing of the flutes.

7. A machine for producing drills starting from elongated members comprising a grindstone adapted to recess gouges in the elongated member, means for rotating same at a very high speed, a hollow spindle inside which the elongated members are adapted to move in succession, chuck members mounted at the end of said hollow shaft facing said grindstone for retaining and releasing the first one of said elongated members, a cradle carrying said hollow spindle, a horizontal pivot round which said cradle is adapted to rock, a second grindstone adapted to engage the elongated members the flutes of which have been recessed by said first grindstone for relieving its surface the axis of said pivot being in the same plane as the cradle pivot, a threaded reproducing member rigid with the hollow spindle and a nut cooperating therewith for imparting to the spindle and to at least the foremost elongated member in the spindle a rotary and translational movement for the recessing of the flutes and means coaxial with the pivot of the cradle for giving the nut its rotation movement.

8. A machine for producing drills starting from elongated members comprising a grindstone adapted to recess flutes in the elongated member, means for rotating same at a very high speed; a hollow spindle inside which the elongated members are adapted to move in succession, chuck members mounted at the end of said hollow shaft facing said grindstone for retaining and releasing the first one of said elongated members, a cradle carrying said hollow spindle, a horizontal pivot round which said cradle is adapted to rock, a second grindstone adapted to engage the elongated members the flutes of which have been recessed by said first grindstone for relieving its surface the axis of said pivot being in the same plane as the cradle pivot, a threaded reproducing member rigid with the hollow spindle and a nut cooperating therewith for imparting to the spindle and to at least the foremost elongated member in the spindle, a rotary and translational movement for the recessing of the flutes and means coaxial with the pivot of the cradle for giving the nut its rotative movement means for turning the elongated member after one reciprocation thereof through 180° round its axis and a differential interconnecting said means for giving the nut its rotation movement and said means for turning the elongated member through 180° and adapted to compensate for the progression of the spindle at each half revolution of the foremost elongated member.

9. A machine for producing drills starting from elongated members comprising a grindstone adapted to recess flutes in the elongated member, means for rotating same at a very high speed, a hollow spindle inside which the elongated members are adapted to move in succession, chuck members mounted at the end of said

hollow shaft facing said grindstone for retaining and releasing the first one of said elongated members, a cradle carrying said hollow spindle, a horizontal pivot round which said cradle is adapted to rock, a second grindstone adapted to engage the elongated members the flutes of which have been recessed by said first grindstone for relieving its surface the axis of said pivot being in the same plane as the cradle pivot and means for applying to the hollow spindle a rotary and translational movement with reference to the cradle, springs urging the cradle into a position of cooperation between the elongated member in the cradle and the first grindstone and means for locking the cradle in its other position corresponding to cooperation between said elongated member and the second relieving grindstone.

10. A machine for producing drills starting from elongated members comprising a grindstone adapted to recess flutes in the elongated member, means for rotating same at a very high speed, a hollow spindle inside which the elongated members are adapted to move in succession, chuck members mounted at the end of said hollow shaft facing said grindstone for retaining and releasing the first one of said elongated members, a cradle carrying said hollow spindle, a horizontal pivot round which said cradle is adapted to rock, a second grindstone adapted to engage the elongated members the flutes of which have been recessed by said first grindstone for relieving its surface the axis of said pivot being in the same plane as the cradle pivot, a reproducing member having a longitudinally conical surface rigid with the hollow spindle and a nut cooperating therewith for imparting to the spindle and to at least the foremost elongated member in the spindle a rotary and translational movement for the recessing of the flutes, springs adapted to urge the cradle in a given direction during the forward operative stroke of the spindle and a roller adjustably mounted on the machine and serving as a stop for the cradle when urged by said springs.

11. A machine for producing drills starting from elongated members comprising a grindstone adapted to recess flutes in the elongated member, means for rotating same at a very high speed, a hollow spindle, a clamp inside said spindle adapted to cooperate with the nose of the spindle for holding the foremost elongated member therein, a clamp drawing member holding said clamp adapted to reciprocate inside said spindle and provided with a longitudinal channel inside which the elongated members are adapted to move, means for reciprocating said clamp drawing member, a cradle carrying said hollow spindle, a horizontal pivot round which said cradle is adapted to rock, a second grindstone adapted to engage the recessed spindle for relieving its surface and the axis of which is in the same plane as the cradle pivot and means for applying to the hollow spindle a rotary and translational movement with reference to the cradle.

12. A machine for producing drills starting from elongated members comprising a grindstone adapted to recess flutes in the elongated member, means for rotating same at a very high speed, a hollow spindle, a clamp inside said spindle adapted to cooperate with the nose of the spindle for holding the foremost elongated member therein, a clamp drawing member holding said clamp, adapted to reciprocate inside said spindle and provided with a longitudinal channel inside which the elongated members are adapted to

move, means for reciprocating said clamp drawing member, a gravity distributor adapted to feed the elongated members in succession into the channel inside the clamp-drawing member, a cradle carrying said hollow spindle, a horizontal pivot round which said cradle is adapted to rock, a second grindstone adapted to engage the recessed spindle for relieving its surface and the axis of which is in the same plane as the cradle pivot and means for applying to the hollow spindle a rotary and translational movement with reference to the cradle.

13. A machine for producing drills starting from elongated members comprising a grindstone adapted to recess flutes in the elongated member, means for rotating same at a very high speed, a hollow spindle, a clamp inside said spindle adapted to cooperate with the nose of the spindle for holding the foremost elongated member therein, a clamp drawing member holding said clamp adapted to reciprocate inside said spindle and provided with a longitudinal channel inside which the elongated members are adapted to move, means for reciprocating said clamp-drawing member, a distributor for the elongated members comprising means for placing the elongated members in succession in front of said channel and means for pushing said elongated members into said channel for the flute recessing position of the cradle, a cradle carrying said hollow spindle, a horizontal pivot round which said cradle is adapted to rock, a second grindstone adapted to engage the recessed spindle for relieving its surface and the axis of which is in the same plane as the cradle pivot and means for applying to the hollow spindle a rotary and translational movement with reference to the cradle.

14. A machine for producing drills starting from elongated members comprising a grindstone adapted to recess flutes in the elongated members, means for rotating same at a very high speed; a hollow spindle, a clamp inside said spindle adapted to cooperate with the nose of the spindle for holding the foremost elongated member therein, a clamp drawing member holding said clamp adapted to reciprocate inside said spindle and provided with a longitudinal channel inside which the elongated members are adapted to move, means for reciprocating said clamp-drawing member, means for retaining the elongated member as soon as it is released by the clamp, means for ejecting the recessed elongated member from said retaining means through an impulse exerted by the next elongated member, a cradle carrying said hollow spindle, a horizontal pivot round which said cradle is adapted to rock, a second grindstone adapted to engage the recessed spindle for relieving its surface and the axis of which is in the same plane as the cradle pivot and means for applying to the hollow spindle a rotary and a translational movement with reference to the cradle.

15. A machine for producing drills starting from elongated members comprising a first grindstone adapted to recess the flutes in the elongated members, means for rotating same at a very high speed, a second grindstone for relieving the periphery of the drills except in the vicinity of the flutes for forming ribs along same, means for imparting to an elongated member a combined movement longitudinally to and round its axis during operation with each grindstone in succession, along lines respectively oblique with reference to the axis of the first grindstone and parallel with that of the relieving grindstone,

and means for adjusting the slope of the first recessing grindstone with reference to the direction of progress of the elongated members.

16. A machine for producing drills starting from elongated members comprising a grindstone adapted to recess flutes in the elongated member, means for rotating same at a very high speed, a hollow spindle, a clamp inside said spindle adapted to cooperate with the nose of the spindle for holding the foremost elongated member therein, a clamp drawing member holding said clamp adapted to reciprocate inside said spindle and provided with a longitudinal channel inside which the elongated members are adapted to move, means for reciprocating said clamp drawing member, a cradle carrying said hollow spindle, a horizontal pivot round which said cradle is adapted to rock, a second grindstone adapted to engage the recessed spindle for relieving its surface and the axis of which is in the same plane as the cradle pivot, means for applying to the hollow spindle a rotary and translational movement with reference to the cradle and means controlling the operation of the clamps and adapted to slide longitudinally over the cradle.

17. A machine for producing drills starting from elongated members comprising a grindstone adapted to recess flutes in the elongated member, means for rotating same at a very high speed, a hollow spindle inside which the elongated members are adapted to move in succession, a cradle carrying said hollow spindle, a horizontal pivot round which said cradle is adapted to rock, a second grindstone adapted to engage the elongated member the flutes of which have been recessed by said first grindstone for relieving its surface and the axis of which is in the same plane as the cradle pivot, a threaded interchangeable and removable reproducing member rigid with the hollow spindle and an interchangeable and removable nut cooperating therewith for imparting to the spindle and to at least the foremost elongated member in the spindle a rotary and translational movement for the recessing of the flutes.

18. A machine for producing drills starting from elongated members comprising a grindstone adapted to recess gouges in the elongated member, means for rotating same at a very high speed, a hollow spindle, a clamp inside said spindle adapted to cooperate with the nose of the spindle for holding the foremost elongated member therein, a clamp drawing member holding said clamp adapted to reciprocate inside said spindle and provided with a longitudinal channel inside which the elongated members are adapted to move, means for reciprocating said clamp drawing member, a first electric motor actuating said means, a cradle carrying said hollow spindle, a horizontal pivot round which said cradle is adapted to rock, a second electric motor for rocking said cradle, a second grindstone adapted to engage the elongated member the gouges of which have been recessed by said first grindstone for relieving its surface and the axis of which is in the same plane as the cradle pivot, means for applying to the hollow spindle a rotary and translational movement with reference to the cradle, a third electric motor actuating said last means 70 a distributor for feeding the elongated members into the longitudinal channel of said clamp drawing member, a fourth electric motor for actuating said distributor, means for turning the elongated member after one reciprocation of the elongated 75 member through 180° round its axis, a fourth

15

electric motor for actuating said turning means, and a controller actuated by said third electric motor for controlling said other electric motors in due sequence.
